ERNEST O. FREDERICS, OF BRONXVILLE, NEW YORK, ASSIGNOR TO E. FREDERICS, INC.,
OF NEW YORK, N. Y., A CORPORATION OF NEW YORK

CLOSING CLIP

Application filed April 14, 1931. Serial No. 529,937.

This invention relates to an improved form of clip adapted for use in closing the ends of compound pads, sachets, or tubes of the type employed in connection with the permanent waving of the hair.

In processes now commonly employed for the production of a permanent wave in human hair it is customary to enclose a lock of the hair, after appropriately twisting it about a bobbin, in a tube which is extended to a point adjacent the scalp. Heat is applied and steam is developed within the tube. To prevent the escape of the steam at the end of the tube adjacent the scalp a clip is employed at this end to tightly clamp the tube around the hair.

It has been a primary object of the present invention to provide a simple but effective clip which may be suitably employed for this purpose and one which is reliable in its action and yet easy to remove when the heat treatment is completed. Devices which have been employed heretofore have usually been either difficult to apply or remove from the end of the tube or have been unreliable in their operation so that there has been danger of their becoming released prematurely and permitting the escape of steam against the scalp. The improved clip contemplated by the present invention is formed of few parts readily produced and put together, is positively held in its clamping condition and may be readily released by a slight pressure against a pair of finger pieces. The new clip is made light in construction and yet, due to an improved leverage action provided by the form and arrangement of the parts, it may be clamped about the end of a tube or pad with greater facility than prior devices of this general character.

Other objects and advantages of the invention will appear from the detailed description of an illustrative form of the invention which will now be given in conjunction with the accompanying drawing in which:

Figure 1 is a sectional view illustrating a tube enclosing a lock of hair wound on a bobbin and having a clip of the improved form applied to one end.

Figure 2 is a face view of the clip shown

in its opened position, a part being shown in dot and dash-lines to indicate the relation when the clip is closed.

Figure 3 is a sectional view of a detail, taken along the line 3-3 of Figure 2.

Figure 4 is a top view of the device as shown in Figure 2.

Figure 5 is a sectional view through the clip taken along the line 5-5 of Figure 2, and

Figure 6 is a sectional view taken along the curved line 6-6 of Figure 2.

Referring now to the drawing there is shown a lock or strand of hair 10 wound around a bobbin 11 and appropriately secured to the latter adjacent the outer end. The bobbin and twisted hair are inserted in a jacket or tube 12 which may be of any suitable form and may, if desired, be lined or packed in a conventional way. The tube may, if desired, be formed by the outer wrapper now commonly connected with pads employed in the waving of human hair. At its outer end the tube is preferably closed by means of a wad of cotton 13 or the like, while at its lower or inner end, which is adjacent the scalp, it is closed by being pinched together around the hair by means of a clip designated generally by the numeral 14 in Figure 1.

The clip 14 may comprise a main body portion composed of a pair of plates 15 and 16 of substantially the same contour and produced preferably by stamping from a piece of sheet metal such as steel or the like. At one end the plates are fastened together by means of a rivet 17 but are spaced apart by means of the end of a trigger member 28 which is clamped between the two plates. The mounting of the trigger is such that it may pivot freely about the rivet to effect the clamping operation. On the side opposite the head of the rivet it is provided with a washer 18 which, for reasons that will be later explained, is of larger diameter than the head of the rivet. In order to provide a somewhat greater leverage action in the clamping of the tube the pivotal axis provided by the rivet 17 is placed approximately $\frac{1}{2}$ " closer to the center of the clamping opening of the tube than has been commonly

the case in prior clip constructions. In this way a force of given magnitude applied to the ends of the clip, as will be explained, will produce a greater closing pressure against the tube.

At their upper or free ends the plates 15 and 16 are provided with finger pieces 19 and 20 respectively, the finger piece 19 having a narrow neck which is passed through an opening 21 in a corresponding portion of the plate 16. The two plates are provided with forward extensions 22 and 23 which at their ends are flared slightly, outwardly, so as to permit the trigger element to be readily forced between them. In the extension 22 and a portion of its plate 15 there is provided an arcuate series of tabs or offsets 24 providing a series of shoulders 25 on the side toward the plate 16. These shoulders are arranged in an arc about a center slightly eccentric to the axis of the rivet 17 and are adapted to cooperate with a shoulder 26 formed by a similar tab 27 struck out at the side of an extension of the trigger element. The arrangement of the shoulders 25 is such that the successive ones approach more closely to the axis of the rivet 17 from the free end 22 toward the back of the plate 15. This arrangement provides a somewhat easier action and a more gradual tightening of the clip when the teeth are engaged, than is the case when the ratchet teeth are arranged concentrically with respect to the rivet. A finger piece or handle 29 is formed as an extension of the trigger element to assist in operating the same.

In order to reduce the weight of the clip as far as possible it has been provided with a number of openings 30, in the trigger element as well as in the plates 15 and 16. The general contour of the parts, furthermore, is such as to reduce to a minimum the amount of metal employed and hence the weight of the clip.

In applying the clip it is opened up to the full line position shown in Figure 2 and it is then slipped over the end of the tube 12 which is adjacent the scalp. The trigger element is then rocked by means of the handle 29 toward the main portion of the clip, the end of the trigger being guided between the flared ends 22 and 23 while the tab 27 simply ratchets over the inner sides of the tabs 24 until the tube is clamped tightly around the hair. At this time the tab 27 will become engaged behind one of the shoulders 25, as best shown in Figure 6. Due to the normal pressure of the plates 15 and 16 toward each other the trigger will be quite positively held in latched position until intentionally released. When it is desired to remove the clip the two finger pieces 19 and 20 are squeezed between a finger and the thumb. On account of the stiffening effect of the washer 18 the movement of the finger

pieces toward each other will cause a bending of the plate 15 outwardly to an extent sufficient to disengage the shoulder 25 from the tab 27. When the trigger is thus released the clip may be readily opened up and removed from the tube.

While an illustrative form of the invention has been disclosed in considerable detail it will be understood that various changes may be made in the form and arrangement of the parts without departing from the general spirit and scope of the invention.

What I claim is:

1. In a device of the class described a pair of co-extensive spaced plates, means for securing said plates adjacent one end, an element pivotally mounted on said means and adapted to be rocked between said plates, inter-engaging shoulders carried by said element and one of said plates, and finger pieces formed at the outer end of said plates at the same radial distance from said means adapted upon being squeezed together to effect disengagement of said shoulders.

2. In a device of the class described a pair of spaced plates, means for securing said plates adjacent one end, said means having a head at one end, a washer of larger diameter than said head mounted on said means adjacent its opposite end, a clamping element adapted to be rocked between said plates, inter-engaging shoulders on said element and one of said plates, and finger pieces carried by said plates at the same radial distance from said means for forcing the free ends of the same apart.

3. In a device of the class described a pair of pivoted jaws, one of said jaws comprising a pair of co-extensive spaced plates, inter-engaging shoulders carried by one of said plates and the other of said jaws, means for securing said plates adjacent one end, means directly in line at the same radial distance from said securing means for forcing the free ends of said plates apart to disengage said shoulders, and means for stiffening one of said plates.

4. In a device of the class described a pair of co-extensive spaced plates, means for securing said plates adjacent one end, an element pivotally mounted on said means and adapted to be rocked between said plates, inter-engaging shoulders carried by said element and one of said plates, finger pieces carried by said plates in planes parallel to the plates, said finger pieces being on opposite sides relative to each other from the corresponding plates and being adapted upon being squeezed together to effect disengagement of said shoulders, and means for stiffening the plate not provided with said shoulder.

5. In a device of the class described a pair of spaced plates riveted only adjacent one end, an element pivotally mounted between

5 said plates on the rivet joining the same, and inter-engaging shoulders integral with said element and one of said plates the shoulders on one of said elements being arranged in the arc of a circle eccentric with respect to the axis of said rivet.

6. In a device of the class described a pair of pivotally mounted clamping elements, a series of shoulders provided on the face of 10 one of said elements, said shoulders being arranged in an arc eccentric to the pivot of said elements, and a shoulder carried by the other of said elements adapted to cooperate with said series of shoulders.

15 In testimony whereof, I have signed my name to this specification this 10th day of April, 1931.

20 ERNEST O. FREDERICKS.
